UNITED STATES PATENT OFFICE

158,407

ROTOR-EQUIPPED AIRCRAFT

Raymond Aubrey Pullin, North Stoneham, near Eastleigh, and Harold Bolas, Salvington Hill, Worthing, England, assignors to The Cierva Autogiro Company Limited, London, England, a British company

Application June 21, 1948, Serial No. 147,108

Term of patent 14 years

(Cl. D71—1)

To all whom it may concern:

Be it known that we, Raymond Aubrey Pullin, a subject of the King of Great Britain, residing at The Old Rectory Hotel, Stoneham Lane, North Stoneham, near Eastleigh, Hampshire, England, and Harold Bolas, a subject of the King of Great Britain, residing at The Barn, Swandeans Corner, Salvington Hill, Worthing, Sussex, England, have invented a new, original and ornamental Design for a Rotor-Equipped Aircraft, of which the following is a specification, reference being had to the accompanying drawings, forming a part thereof.

Figure 1 is a perspective three-quarter front view, looking somewhat downwardly, of a rotor-equipped aircraft embodying the design of the present invention; and

Figures 2, 3 and 4 are, respectively, left side,

top plan and front elevational views of the aircraft shown in Figure 1.

We claim:

The ornamental design for a rotor-equipped aircraft, substantially as shown.

RAYMOND AUBREY PULLIN.
HAROLD BOLAS.
